[57] CLAIM

The ornamental design for a candlelamp, as shown and described.

DESCRIPTION

FIG. 1 is a side elevational view of a candlelamp showing our new design, the opposite side being identical;

FIG. 2 is a top plan view thereof;

FIG. 3 is a cross-sectional view thereof as taken along line III—III of FIG. 1;

FIG. 4 is a bottom plan view thereof;

FIG. 5 is a fragmentary side elevational view thereof, a portion of the outer wall being broken away for purposes of disclosure;

The broken lines are shown for illustrative purposes only.

FIG. 1

FIG. 3

FIG. 2

FIG. 4

FIG. 5
